UNITED STATES PATENT OFFICE.

CLEMENT F. STREET AND NATHAN M. LOWER, OF SCHENECTADY, NEW YORK, ASSIGNEES TO THE LOCOMOTIVE STOKER COMPANY, OF WILMERDING, PENNSYLVANIA, A CORPORATION OF PENNSYLVANIA.

DISTRIBUTER FOR MECHANICAL STOKERS.

1,195,529.

Specification of Letters Patent. Patented Aug. 22, 1916.

Application filed January 12, 1912. Serial No. 670,835.

To all whom it may concern:

Be it known that we, CLEMENT F. STREET and NATHAN M. LOWER, both citizens of the United States, residing at Schenectady, in the county of Schenectady and State of New York, have invented a certain new and useful Improvement in Distributers for Mechanical Stokers, of which the following is a specification.

10 This invention relates to mechanical stokers, and more particularly to the construction of distributers adapted to be operated by a fluid pressure blast or jet for delivering and spreading the fuel over the area 15 of the furnace grate.

This improvement is particularly designed for use in connection with mechanical stokers for locomotive boilers, such as shown and described in our prior application Ser. 20 No. 652,462, filed October 2, 1911, and one of the objects of our present improvement is to provide a detachable distributer which may be inserted from the inside of the boiler furnace, and having wide flaring wings upon 25 the inside of the furnace for more effectually and evenly distributing the fuel over the grate.

Another object is to provide an improved form of distributer whereby the blast is 30 made more effective, particularly for handling finely divided lump fuel.

In the accompanying drawings: Figure 1 is a vertical longitudinal section of one form 35 of our improved distributer; Fig. 2, an outside end view of the same; Fig. 3, an inside end view; Fig. 4, a plan, the boiler shell being shown in section; Fig. 5, a side elevation showing a modification, a part being indicated in vertical section; Fig. 6, a horizontal 40 section of the same; Fig. 7, an end view of the modification shown in Figs. 5 and 6; and Fig. 8, a transverse section taken on the line 8—8 of Fig. 5.

As shown in the drawings, the fuel is delivered by pipe, 20^b, to the elbow, 20^a, of the distributer, which is provided with air inlet, 27, and the steam or other fluid pressure connection, 28, for the blast, as set forth in our prior application above referred to.

50 According to our present construction, the distributer device is formed in detachable parts, the elbow part, 20^a, being located at the desired point outside the boiler shell, and the distributer, 20, being inserted from in-

side of the fire box of the boiler through the 55 opening made for this purpose in the front leg, 21, of the boiler, and then fitted within the cylindrical flange, 30, of the elbow, 20^a, to which it may be detachably fastened in any convenient manner, as by means of connecting plate, 26, having a rivet or projection, 22, adapted to extend through openings in the flange, 30, and the distributer, 20, and a bolt, 29, for securing the plate to the elbow, 20^a. The distributer may then be readily detached by loosening the nut of the bolt, and taking off the connecting plate. The tubular shank of the distributer thoroughly protects the metal of the boiler shell around the fuel opening.

With this improved means for attaching the distributer, the inside end or hood may be flared out much wider than the opening through the boiler shell and thereby operate to distribute the fuel more effectually and 75 over a wider range of the grate area.

As the particular distributer shown in the drawings is designed to be used in a central or intermediate position from which it is desired to cover the middle and rear portion of the grate, the inside end or hood of the distributer is formed with widely flaring curved wings, 23, extending over and downward, the lower end or lip portion, 25, of which projects below the full discharge 85 mouth, and is provided with concave and deflecting surfaces adapted to scatter the fuel over the middle and rear portions of the grate. The inclination of the deflecting surfaces may be made to suit different conditions, as to fuel and equipment. The bottom portion of the distributer may be made thicker, as at 24, thus forming an upwardly inclined surface for deflecting the fuel over into the curved wing portions. A central 90 rib, 32, divides the wing portions and may have a broad edge forming a deflecting surface for diverting some fuel back to the rear portion of the grate.

In order that the fluid pressure blast may 100 operate more efficiently in handling fuel, particularly where finely divided lump fuel is employed, the lower portion of the elbow, 20^a, and the tubular shank of the distributer may be made oval or V shaped in cross section, as shown in Figs. 5 to 8 of the drawings. In this way the walls of the distributer shank are brought closer to the blast

nozzle, and form a narrow trough through which the fuel may be readily driven by the blast of steam or other fluid under pressure. In this form of the distributor, the shank portion may be provided with segmental ribs, 31, for the purpose of fitting snugly within the cylindrical flange of the elbow, 20^a, and the opening through the boiler shell.

When a distributor becomes burned out 10 due to the great heat of the furnace to which they are subjected, it may be readily detached and a new one inserted from the inside of the fire box.

Having now described our invention, what 15 we claim as new, and desire to secure by Letters Patent, is:

1. In a mechanical stoker, the combination with a furnace wall having an opening, of a fuel distributor comprising an elbow 20 outside the furnace wall provided with fuel and fluid pressure connections, and having a flanged opening, a tubular shank extending through said opening and detachably connected to said flange, and a flaring distributor 25 hood of greater width than said opening formed integrally upon the end of the shank within the firebox.

2. In a mechanical stoker, the combination with a furnace wall having an opening, of a 30 fuel distributor comprising an elbow outside said wall and provided with fuel and fluid pressure connections, a distributing hood inside said wall and having an integral tubu-

lar shank extending through said opening, and detachable means connecting the shank 35 with said elbow, said hood having flaring wing portions extending beyond and curved over and downward below the fuel discharge end of the shank portion.

3. In a mechanical stoker, the combination 40 with a furnace wall having a circular opening, of a fuel distributor having a tubular portion of V shaped section extending through said opening and provided with segmental ribs fitting within said opening, 45 and a fluid nozzle discharging longitudinally through said tubular portion adjacent to the bottom thereof.

4. In a mechanical stoker, a fuel distributing device comprising an elbow formed 50 with a V-shaped lower portion and a cylindrical flanged opening, a fluid pressure connection at the V-shaped portion, and a distributor, also formed with a V-shaped lower portion, adapted to extend through an opening in a furnace wall and provided with flanges fitting within the flanged opening of the elbow and the opening in the furnace wall.

In testimony whereof we have hereunto set 60 our hands.

CLEMENT F. STREET.
NATHAN M. LOWER.
